UNITED STATES PATENT OFFICE

JAMES C. DAY, OF SOUTH ORANGE, NEW JERSEY, ASSIGNOR TO THE WHITEHEAD AND HOAG COMPANY, OF NEWARK, NEW JERSEY, A CORPORATION OF NEW JERSEY

BUTTON RECEPTACLE

Application filed December 14, 1928. Serial No. 326,078.

This invention relates to a new and improved button receptacle.

In a great many States, a person who desires to hunt or trap wild game, or to fish 5 is required to obtain from the State a license for so doing. It is usually required by law that when such a person is engaged in the activity for which he has taken a license, he must carry with him a button or tag carrying 10 on its face indicia asserting the fact that he is the holder of such a license and this button or tag must at all times be exposed to view. In addition, the licensee is required to have 15 with him the license itself.

The main object of my invention is to provide a button which will not only carry on 20 its face the required indicia, but which will itself form a convenient receptacle in which the license itself may be carried.

I am aware that certain buttons have been made with provision for carrying a license, but in all such articles hitherto known, there 25 has not been adequate provision to insure the fact that the license will be held securely in the receptacle provided for it and another object of my invention is to provide a button receptacle of such a design that when a license is placed therein, it will be secured 30 therein with no danger of its becoming displaced.

Another object of my invention is to provide a structure in which the receptacle for the license will be made by the malformation 35 of the shell or rear plate of the button without the necessity of providing a separate and independent member in order to obtain such receptacle.

Other objects and advantages relate to the 40 size, shape and arrangement of parts, all as will more fully appear from the following description taken in connection with the accompanying drawings in which:

Figure 1 is a front elevation of the preferred embodiment of my device.

Figure 2 is a rear elevation of the device.

Figure 3 is a section on line 3—3 of Figure 1.

Figure 4 is a section on line 4—4 of Figure 1.

Figure 5 is a perspective view of the shell or back plate of the device.

Figure 6 is a view similar to Figure 1 of a modified form of my device.

Figure 7 is a rear elevation of such modified 55 form.

Figure 8 is a section on line 8—8 of Figure 6.

Figure 9 is a section on line 9—9 of Figure 6.

Figure 10 is a perspective view of the shell or back plate of the modified form shown in 60 Figure 7.

My button 1 consists of a front plate 2, preferably circular in form and having its 65 edge return bent to form an annular groove 3. The indicia carrying material 4 having, when desired, indicia thereon, none here being shown, is positioned on the front surface of front plate 2 and has its edge return bent 70 around the edge of the front plate 2 into the annular groove 3 with a portion of such edge resting against the back of front plate 2.

The shell or back plate 5 is formed with 75 annular rim 6 and has its central portion 7 dished inwardly. A pair of spaced apertures 8 and 9 are formed in central portion 7 adjacent rim 6. Beneath apertures 8 and 9 and in central portion 7 I form a slot 10. The part of central portion 7 adjacent the lower 80 edge of slot 10 is bent outwardly to form the back and sides of a pocket or receptacle 11 which will be formed between it and front plate 2 when the parts are assembled in the manner hereinafter described. In the lower 85 end of the pocket side 11 is formed an aperture 12 for a purpose hereinafter to be described.

For the purpose of attaching the button receptacle to a garment, I provide a pin 13. As 90 perhaps may best be seen from Figures 2 and 4, pin 13 has an oppositely deflected portion 14 positioned between the central portion 7 of back plate 5 and front plate 2 and has one end extending outwardly through aperture 8 95 and formed into a coil 15 from which extends the pin portion 16 to engage a loop 17 formed upon the opposite end of portion 14 after the same has been extended outwardly through aperture 9. Pin portion 16 at its central 100

point has an inwardly extending curved portion 18 of a size and shape to extend into slot 10 when the pin portion 16 is engaged with loop 17.

5 With the pin 13 is position on back plate 5, the annular rim 6 of back plate 5 is placed in position against the inner surface of the indicia carrying material 4, which is positioned in the annular groove 3 of the 10 front plate 2, the inner edge of rim 6 abutting against the part of the indicia carrying material 4 which is positioned against the rear surface of front plate 2. The annular rim of front plate 2 being deflected inwardly 15 and rim 6 of back plate 5 being deflected outwardly the parts will be firmly locked in position when they have been assembled in the manner just described.

When back plate 5 is in position on front 20 plate 2, the portion 14 of pin 13 will be held against the inner face of front plate 2 and such portion 14 being oppositely deflected the pin 13 will be held rigidly in position. With parts in the assembled relation, the 25 space between the part 11 of back plate 5 and the inner face of front plate 2 will form a receptacle into which a license or other card may be placed. When a license is in such receptacle and the pin portion 16 has been 30 passed through the clothing of the wearer and its end positioned in loop 17, the curved portion 18 of the pin portion 16 will extend into slot 10 and engage the license to hold it firmly in the receptacle. The aperture 12 is 35 provided so that a finger or other object may be inserted into the receptacle to aid in forcing the license out when it is so desired.

In the modified form shown in Figures 40 6 to 10 inclusive, the difference in construction consists in the shape of the back plate although the object to be accomplished is the same that is the formation of a receptacle between the front plate and the back plate by the malformation of the back plate.

45 In this embodiment of my invention, I show a front plate 18 similar in form to front plate 2 and having an annular groove 19. Indicia carrying material 20 is placed in position on front plate 18 in the same manner that the 50 indicia carrying material 4 was placed in position on front plate 2.

The back plate 21 is provided with an annular rim 22 and has spaced elongated struck-out portions 23 and 24 which are bent inwardly in parallel relation. In the upper 55 part of back plate 21 I form a U-shaped slot 25 having its opposite ends adjacent rim 22. The upper portion 26 of back plate 21 is bent inwardly for a purpose hereinafter to be described. In the lower part of back plate 21 I provide an aperture 27.

A pin 28 similar in shape to pin 13 has its 60 oppositely bent portion 29 positioned against the inner surface of the inwardly bent portion 26 of back plate 21 and has its spring end 30

extending outwardly through one end of U slot 25 and has its other end carrying a loop 31 extending outwardly through the other end of U slot 25. The pin portion 32 is formed with an inwardly curved portion 33 70 similar to curved portion 18 on pin 13.

When the back portion 21 has been assembled with front plate 18 and indicia carrying material 20, with rim 22 locked in annular groove 19, the oppositely bent portion 29 of pin 28 will be held against the rear surface of front plate 18 by the inwardly bent portion 26 of back plate 21. The relation of parts is such that when they are in the assembled position, the inwardly extending portions 23 and 24 of back plate 21 will contact with the rear surface of front plate 18 and function as side members of the receptacle formed between the rear face of front plate 18 and the inner face of back plate 21, the portion 26 being bent inwardly into contact with the rear face of front plate 18. A license or other indicia carrying card may be inserted through U slot 25 into the space between front plate 18 and back plate 21. A aperture 27 is provided so that a finger or other object may be inserted therein to assist in removing a license from the receptacle. When a license is in the receptacle and the pin portion 32 of pin 28 has been passed through the clothing of the wearer and engaged with loop 31, the curved portion 33 will extend inwardly and engage the license to secure it in position.

It will be understood that further modifications of my device may be made without departing from the spirit of my invention. It will also be understood that the size, shape and particular arrangement of parts may also be varied as desired, for although I have shown and described specific structures and form of part as exemplification of embodiments of my invention, I do not desire to restrict myself to the exact size, shape, or relation of parts as various changes may be made within the scope of the appended 100 claims.

I claim:

1. A button receptacle comprising a front plate, a back plate secured at its edge to the front plate, said back plate having a slit 115 therein and a portion of the back plate bordering one side of said slit being pressed into a position offset from the portion on the other side of said slit to render available a receptacle between the front and back plates adapted to receive an article through said slit, the portion bordering the other side of the slit being formed into a holding means for a 120 means for attaching the button to a garment, and an attaching means secured in such holding means.

2. A button receptacle comprising a front plate, a back plate secured at its edge to the front plate, said back plate having a slit 130

therein and a portion of the back plate bordering one side of said slit being pressed into a position offset from the portion on the other side of said slit to render available a 5 receptacle between the front and back plates adapted to receive an article through said slit, and an attaching pin having a portion adapted to overlie said opening to normally maintain an article in the receptacle.

10 3. A button receptacle comprising a front plate, a back plate secured at its edge to the front plate, said back plate having a slit therein and a portion of the back plate bordering said slit being depressed in a direction 15 away from the front plate to form with the front plate a receptacle with an opening at the slit, and an attaching pin having a portion adapted to overlie said opening to normally maintain an article in the receptacle.

20 4. A button receptacle comprising a front plate, a back plate secured at its edge to the front plate, said back plate having a slit therein and a portion of the back plate bordering one side of said slit being pressed into 25 a position offset from the portion on the other side of said slit to render available a receptacle between the front and back plates adapted to receive an article through said slit, said receptacle having side walls formed 30 from offset portions of said back plate, the portion bordering the other side of the slit being formed into a holding means for a means for attaching the button to a garment, and an attaching means secured in such holding 35 means.

40 5. A button receptacle comprising a front plate, a back plate secured at its edge to the front plate, said back plate having a slit therein and a portion of the back plate bordering one side of said slit being pressed into a position offset from the portion on the other side of said slit to render available a receptacle between the front and back plates 45 adapted to receive an article through said slit, and an attaching pin having a portion adapted to overlie said opening to normally maintain an article in the receptacle, and said receptacle having side walls formed from offset portions of said back plate.

50 6. A button receptacle comprising a front plate, a back plate secured at its edge to the front plate, said back plate having a slit therein and a portion of the back plate bordering one side of said slit being pressed into 55 a position offset from the portion on the other side of said slit to render available a receptacle between the front and back plates adapted to receive an article through said slit, and a finger opening in the receptacle at the end 60 opposite the slit.

65 7. A button receptacle comprising a front plate, a back plate secured at its edge to the front plate, said back plate having a slit therein and a portion of the back plate bordering said slit being depressed in a direction

away from the front plate to form with the front plate a receptacle with an opening at the slit, and a finger opening in the receptacle at the end opposite the slit.

In witness whereof I have hereunto set my 70 hand this 4th day of December, 1928.

JAMES C. DAY.
